US00D953323S

(12) **United States Design Patent** (10) **Patent No.:** **US D953,323 S**
(45) **Date of Patent:** ** *May 31, 2022

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/795,821**

(22) Filed: **Jun. 21, 2021**

Related U.S. Application Data

(63) Continuation of application No. 29/761,618, filed on Dec. 10, 2020, which is a continuation of application

No. 29/689,359, filed on Apr. 29, 2019, now Pat. No. Des. 905,051, which is a continuation of application No. 29/543,521, filed on Oct. 26, 2015, now Pat. No. Des. 847,010, which is a continuation of application No. 29/501,752, filed on Sep. 8, 2014, now Pat. No. Des. 741,726.

(57) CLAIM

The ornamental design for an electronic device, as shown and described.

DESCRIPTION

FIG. 1 is a bottom front perspective view of an electronic device showing the claimed design;

FIG. 2 is a top front perspective view thereof;

FIG. 3 is a top rear perspective view thereof;

FIG. 4 is a bottom rear perspective view thereof;

FIG. 5 is a front view thereof;

FIG. 6 is a rear view thereof;

FIG. 7 is a left side view thereof;
FIG. 8 is a right side view thereof;
FIG. 9 is a top view thereof; and,
FIG. 10 is a bottom view thereof.

The dot-dash broken lines in the figures and the light gray areas within the dot-dash broken lines show portions of the electronic device that form no part of the claimed design.
